UNITED STATES PATENT OFFICE

MORRIS C. SCHERER, OF TEXARKANA, TEXAS

MINING MACHINE

Application filed December 18, 1929. Serial No. 415,056.

This invention relates to improvements in mining machinery and has particular reference to a machine for use within a mine for the purpose of trapping the falling ore or muck.

The principal object of this invention is to produce a trap which will prevent the material being blasted from spreading any great distance from the surface being blasted and to further provide a device wherein the various implements employed for removing the blasted material may be brought up and cooperate with the trap in such a manner as to receive the blasted material and to convey it to a distant point.

Another object of the invention is to produce a device wherein a large percentage of the blasted material may be elevated and dumped into a hopper from which hopper the material may be discharged to a conveyor.

Another object is to produce a device which is simple in construction and one which will not be injured through the pounding of the flying material incident to the explosion.

A further object is to produce a device which may be so adjusted that it will accommodate itself to tunnels or drifts of various widths and heights.

A still further object is to produce a device of this character which is economical to manufacture.

Other objects and advantages will be apparent during the following description.

In the accompanying drawings forming a part of this specification and in which like numerals are employed to designate like parts throughout the same,

Figure I is a side elevation of my device.

Figure II is a top plan view of Figure I, and

Figure III is a rear elevation of Figure I.

In mining it is common to drill holes into the face of the drift into which holes explosive is placed. This explosive is fired with the result that the face of the drift is shattered and considerable rock or muck is dropped onto the floor of the drift. It has been common to transport the material away

by workmen throwing the same into movable cars.

Applicant has provided a device which will catch and elevate most of the material into a hopper in a very simple manner.

In the accompanying drawings wherein for the purpose of illustration is shown a preferred embodiment of my invention, the numerals 5 and 6 refer to tracks laid upon the customary ties 7 upon the floor of the drift. It is upon these rails that I place my device which consists essentially of a primary hopper 8 which hopper has an opening 9 in its bottom for the purpose of discharging material within the hopper to a conveyor placed thereunder. This hopper 8 is mounted upon wheels 11 and 12.

By referring to Figure III it will be noted that the rear wheels are upon separate axles thereby leaving a space therebetween for the conveyor to pass under the hopper. This hopper 8 has a frame supported thereon, which frame may be of any standard shape here shown as four posts designated at 13, 14, 16 and 17. Braces 18 are provided, the purpose of which is obvious. Hingedly secured to the hopper 8 are baffle plates as shown at 19, 21 and 22. These baffle plates have secured thereto cables 23, which cables pass through eyes in the uprights 13 and 14 and are joined to a common pulling cable 24 which cable passes to a drum 26 which may be rotated in any convenient manner.

In order to prevent the flying of material beyond the rear extremity of the hopper I provide a baffle which consists of a central section made up of vertically adjustable plates 27 and 28 and a centrally removable plate 29. These three plates are elevated through the medium of screws 31 and 32. Auxiliary baffle plates are shown at 33 and 34 which are movable through the medium of screws 36 and 37 respectively. The result of this construction is that when my device is placed within a mine drift as shown in the figures and an explosion is set off, the falling material will be confined between the face of the drift and the baffle at the rear thereof. The inclined baffle plates

19, 21 and 22 will also catch a large portion of the material with the result that these baffles may be elevated through the medium of the winding mechanism 26 and may be elevated either independently or collectively, depending entirely upon the arrangement of the ropes. When these baffles have been elevated they will assume the position shown in dotted lines of Figure I with the result 10 that the primary hopper will have an auxiliary hopper formed on the top thereof. By removing the baffle plate 29 the boom of a drag sweep may be extended over the hopper and with the baffle 21 in lower position loose material may be scraped up and dumped in the hopper. When the hopper 15 is filled, a conveyor may be positioned underneath the same and receive material thereon.

It will thus be seen that I have produced 20 a device which will effectively trap flying material and one wherein material may be readily elevated into a hopper for further treatment.

It is to be understood that the form of 25 my invention herewith shown and described is to be taken as a preferred example of the same and that various changes relative to the material, size, shape and arrangement of parts may be resorted to without departing 30 from the spirit of the invention or the scope 95 of the subjoined claims.

Having thus described my invention, I claim:—

1. In a device of the character described, 35 a hopper, a plurality of baffles pivotally secured to said hopper and extending downwardly and outwardly therefrom in such a manner as to form an apron about said hopper, a framework supported on said hopper, 40 means carried by said framework for elevating said baffles, and a vertically disposed baffle secured to said hopper and in the rear thereof for the purpose specified.

2. In a device of the character described, 45 a hopper, a plurality of baffles pivotally secured to said hopper and extending downwardly and outwardly therefrom in such a manner as to form an apron about said hopper, a framework supported on said hopper, 50 means carried by said framework for elevating said baffles, a vertically disposed baffle secured to said hopper and in the rear thereof, said vertically disposed baffle comprising 55 a plurality of plates.

3. In a device of the character described, 60 a hopper, a plurality of baffles pivotally secured to said hopper and extending downwardly and outwardly therefrom in such a manner as to form an apron about said hopper, a framework supported on said hopper, 65 means carried by said framework for elevating said baffles, a vertically disposed baffle secured to said hopper and in the rear thereof, said vertically disposed baffle com-

prising a plurality of plates, and means for adjusting said plates transversely.

4. In a device of the character described, 70 a hopper, a plurality of baffles pivotally secured to said hopper and extending downwardly and outwardly therefrom in such a manner as to form an apron about said hopper, a framework supported on said hopper, 75 means carried by said framework for elevating said baffles, a vertically disposed baffle secured to said hopper and in the rear thereof, said vertically disposed baffle comprising a plurality of plates, means for adjusting said plates transversely, and means for elevating said plates for the purpose 80 specified.

In testimony whereof I affix my signature.

MORRIS C. SCHERER.
